SHOE AND METHOD OF MAKING SAME

Filed June 26, 1943

UNITED STATES PATENT OFFICE

2,375,390

SHOE AND METHOD OF MAKING SAME

John Frederick Smith, Quincy, Mass., assignor to
Compo Shoe Machinery Corporation, Boston,
Mass., a corporation of Delaware

Application June 26, 1943, Serial No. 492,429

17 Claims.

(Cl. 36—34)

This invention relates to shoes and their manufacture and more particularly to the securing of outsoles and heels to the heel seats of lasted shoes.

In the manufacturing of shoes it is usual procedure to complete the lasting operations to secure the upper to the shoe insole, secure the shank stiffener piece in place and then attach the outsole at its heel end to the heel seat of the shoe with staples or tacks. This procedure locates the outsole with respect to the shoe bottom and yet allows the sole to be bent away from the shoe bottom in order to facilitate application of a cement solvent or softener to the cemented surface of the sole and/or upper, prior to placing the assembly in a press for permanently attaching the sole to the shoe bottom as described in the patent to Bresnahan No. 1,893,015.

While the above procedure may be satisfactory for shoes to which a heel is to be secured by nails after the last is withdrawn from the shoe, it has disadvantages when used in manufacturing a shoe to which the heel is to be secured while the shoe is on the last by means of a fastener passing through the bore in the last, as there is no definite means of locating the shank stiffener piece and sole securing staples or tacks with respect to the point where the heel fastener will penetrate the heel seat materials, and it very often occurs that the shank stiffener piece and/or the sole securing staples are placed so that they are in the path of the tools which operate through the last bore to form a hole for, and to insert, the heel fastener, resulting in excessive breakage of the tools and frequent misplacement of the heel fastener causing unnecessary expense and delays in production.

From the above it can readily be seen that accurate positioning and securing of the shank piece to the heel of the shoe is necessary and to this end it has been proposed to pre-drill for, or mark upon, the heel seat materials the location of the heel fastener by tools guided by the last bore. However, this is an added expense and at best it serves only as a visual aid in placing the shank piece and does not prevent placing of the shank piece over a portion of the hole or mark on the heel seat materials, and as the hole or mark is covered and hidden from view when attaching the outsole to the shoe heel seat, the staples, which must be located somewhat to the central portion of the heel seat in order to avoid the dies or knives later used

to cut on or trim the heel end of the sole for reception of the heel, can still be placed in the path of the heel fastener and thereby cause damage to the tools used to drill and drive in place, the heel fastener.

It is, therefore, an object of this invention to provide novel means for securing the heel end of an outsole to the heel seat of a lasted shoe in a manner which is both economically and structurally beneficial.

Another object of the invention is to provide a novel method of placing and securing a shank stiffener piece to the heel seat of a shoe.

A further object of the invention is to provide a shoe with a sole that is securely fastened to the heel seat materials with a fastener which serves as a heel fastener socket.

Still further objects of the invention are to improve heel seat construction of shoes and attachment of heels thereto, and to reduce breakage of tools during such operations.

Other objects of the invention will in fact be obvious and will in part appear hereinafter.

The invention accordingly comprises the several steps and the relation of one or more of such steps with respect to each of the others, and the article possessing the features, properties, and the relation of elements, which will be exemplified in the following disclosure, and the scope of the invention will be indicated in the claims.

For a fuller understanding of the nature and objects of the invention, reference should be had to the following detailed description taken in connection with the accompanying drawing, in which:

Fig. 1 is a fragmentary sectional view of a lasted shoe showing one method of forming a hole in the heel seat materials and outsole of the shoe in alignment with the heel fastener receiving bore of its last;

Fig. 2 is a fragmentary sectional view similar to Fig. 1 but showing the insertion of an eyelet into the sole and heel seat materials and the placing of a shank stiffener piece.

Fig. 3 is a fragmentary sectional view showing the final clinching of the eyelet to secure the sole and shank piece to the heel seat of the shoe;

Fig. 4 is a sectional plan view taken substantially along lines 4—4 of Fig. 6;

Fig. 5 is a fragmentary sectional view of a shoe prepared in accordance with the showings of Figs. 1 to 3 and showing the drilling of the

heel for the reception of the heel fastening screw;

Fig. 6 is a side elevation partially in section of a portion of a completed shoe embodying features of the invention; and

Fig. 7 is a fragmentary sectional view similar to Fig. 3 but on an enlarged scale.

Referring to the drawing, there is shown in Fig. 1, a last 10 having a last pin ferrule 11 forming a heel fastener receiving bore 12, and the usual metal heel plate 13 for clinching the heel seat lasting tacks. Mounted on the last 10 is a shoe which may comprise an upper 14 having its lasting allowance secured to the insole 15 in any desired manner.

An outsole 16 is placed in position on the shoe bottom and the complete assembly is placed on a last pin 17 of a punching and eyelet setting machine having a punch 18 and a die 19. An eyelet 20 is placed on the punch 18 and in operation of such machine the last pin 17 moves upwardly to clamp the shoe against the die 19, and the punch 18 is reciprocated in the bore 21 of the last pin sufficient to form a hole in the heel end of the outsole 16, the insole 15 and any other materials forming the heel seat of the shoe, in alignment with the heel fastener receiving bore 12. After forming the hole the punch 18 continues its reciprocation and drives the eyelet 20 into the hole formed as the die 19 is retracted as illustrated by Fig. 2.

In this condition the forepart and shank portions of the outsole 16 are lifted away from the shoe bottom and a metal shank piece 22 is inserted between the insole 15 and the outsole 16 with the forks 23 straddling the eyelet 20 as illustrated by Fig. 4.

The end of the shank piece 22 may be then located with respect to the ball of the shoe and secured by a tack 24. The outsole 16 may be re-aligned with the shoe bottom and the die 19 is advanced toward the outsole as illustrated in Fig. 3. The die 19 has an inner face 25 so shaped that when it presses against the outer edge of the eyelet 20, it spreads it and clinches it. This spreading of the eyelet 20 rivets the outsole, the shank piece and the insole firmly together, and due to the shape of the shoulder 26 of the punch 18 it also forms a tapered seat or socket 27 in the eyelet 20 for the reception of the head of the heel-attaching screw.

After the eyelet 20 has been spread to rivet the sole to the heel seat of the shoe, the outsole may be attached to the shoe bottom in the usual sole attaching press and the heel end of the outsole prepared for reception of the heel.

A suitable machine for attaching the heel 30 to the shoe is disclosed in the Kenneth W. Macdonald application, Serial No. 365,320, filed November 12, 1940.

In attaching the heel 30, the shoe on its last 10 is located so that the ferrule or fastener receiving bore 12 locates over a last pin 31 and after placing and clamping the heel in position the heel is drilled by a drill 32 held in a spindle 33 guided in the last pin 31.

It can readily be seen that the drill will pass through the eyelet 20 which has been placed in alignment with the last ferrule 11, and also that the drill will not have to penetrate any of the heel seat materials which tend to clog the drill flutes as formerly. It is also apparent that it is impossible for the drill to contact the metal shank piece inasmuch as the passage of the drill

is surrounded by the metal spacing walls of the eyelet 20.

Referring to Fig. 6 a screw 34 is driven into the heel 30 by a driver 35 guided by the last pin 31 and the last ferrule 11, thus the eyelet 20 is seen to act as a screw-receiving socket so that the more the screw is tightened to pull the heel to the shoe, the more the heel seat materials will be held together and this without any danger of the head of the screw pulling through the heel seat materials. The screw contacting portion of the eyelet is shown by Fig. 6 to be formed complementary to the inner screw surface contacting same.

Since certain changes may be made in carrying out the above process and in the product, and modifications effected in the apparatus described for practicing the principle thereof, without departing from the scope of the invention, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having thus described my invention, what I claim as new and desire to secure by Letters Patent is:

1. A shoe having an upper lasted to an insole, an eyelet, an outsole riveted to the central heel seat portion of said insole by said eyelet, a heel, and a fastener passing through said eyelet and securing said heel to said shoe.

2. A shoe having an upper lasted to an insole, an eyelet, an outsole riveted to the heel seat of said insole by said eyelet, a heel, and a headed fastener passing through said eyelet and securing said heel to said shoe, said eyelet having the fastener head contacting portion thereof shaped complementary to the shape of the inner surface of said fastener contacting said eyelet.

3. A shoe having an upper lasted to an insole, an eyelet, an outsole riveted to the heel seat of said insole by said eyelet, a heel, and a screw passing through said eyelet and securing said heel to said shoe, said eyelet having the screw head contacting portion thereof shaped complementary to the shape of the inner surface of the head of said screw contacting said eyelet.

4. A shoe having an upper lasted to an insole, an eyelet, an outsole riveted to the heel seat of said insole by said eyelet, a heel, and a taper-headed screw passing through said eyelet and securing said heel to said shoe, said eyelet having a tapered screw head contacting portion.

5. A shoe having an upper lasted to an insole, an outsole, an eyelet extending through said insole and outsole, and a shank piece between said insole and outsole and having forks straddling said eyelet.

6. A shoe having an upper lasted to an insole, an outsole, an eyelet extending through said insole and outsole, and a shank piece between said insole and outsole and having forks straddling said eyelet, said eyelet having the extremities of its ends spread and clinched for riveting said insole, said shank piece and said outsole together.

7. A shoe having a heel seat comprising a plurality of laminations, an eyelet riveting said laminations together, a heel, and means passing

through said eyelet securing said heel to said heel seat.

8. A shoe having a heel seat comprising a plurality of laminations, a shank piece terminating on said heel seat, an eyelet riveting said laminations and said shank piece together, a heel, and fastening means passing through said eyelet and securing said heel to said heel seat.

9. That improvement in methods of attaching soles to the heel seats of shoes which comprises, forming a hole through the heel seat material of a shoe, forming an aligned hole through the heel seat portion of the outsole, locating an eyelet within the holes thus formed, placing a shank piece between said heel seat material and said heel seat portion of said outsole, and clinching said eyelet for riveting said heel seat material, said shank piece and said heel seat portion of said outsole together.

10. That improvement in methods of attaching soles to the heel seats of shoes which comprises, forming a hole through the heel seat material of a shoe, forming an aligned hole through the heel seat portion of the outsole, locating an eyelet within the holes thus formed, placing a shank piece having spaced portions between said heel seat material and said heel seat portion of said outsole with said portions straddling said eyelet, and clinching said eyelet for riveting said heel seat material, said shank piece and said heel seat portion of said outsole together.

11. That improvement in methods of attaching soles and heels to shoes which comprises, forming a hole through the heel seat material of a shoe, forming an aligned hole through the heel seat portion of the outsole, locating an eyelet in the holes thus formed, placing a heel on said heel seat portion of said outsole, operating a tool through said eyelet for making a hole in said heel, and inserting a fastener through said eyelet into said hole.

12. That improvement in methods of attaching soles and heels to shoes which comprises, forming a hole through the heel seat material of a shoe, forming an aligned hole through the heel seat portion of the outsole, locating an eyelet in the holes thus formed, placing a heel on said heel seat portion of said outsole, operating a tool through said eyelet for making a hole in said heel and placing and tightening a screw in said hole.

13. That improvement in methods of attaching soles and heels to shoes which comprises, forming a hole through the heel seat material of a shoe, forming an aligned hole through the heel seat portion of the outsole, locating an eyelet in the holes thus formed, clinching said eyelet

for riveting said insole and outsole together, placing a heel on said heel seat portion of said outsole, operating a tool through said eyelet for making a hole in said heel, and inserting a fastener through said eyelet into said hole.

14. That improvement in methods of attaching a sole to a shoe mounted on a last having a bore in the heel portion thereof, which comprises operating a tool through said bore for forming holes in the heel seat material of the shoe and in the outsole thereof, locating an eyelet in the hole thus formed, and clinching said eyelet by a tool applied through said bore for riveting said outsole and said heel seat material together.

15. That improvement in methods of attaching a sole to a shoe mounted on a last having a bore in the heel portion thereof, which comprises operating a tool through said bore for forming holes in the heel seat material of said shoe and in the outsole thereof, locating an eyelet in the holes thus formed, placing a heel on the heel seat portion of the shoe, operating a tool through said bore and said eyelet for making a hole in said heel, and inserting a fastener through said bore and into said eyelet and said hole for securing said heel to said shoe.

16. That improvement in methods of attaching a sole to a shoe mounted on a last having a bore in the heel portion thereof, which comprises operating a tool through said bore for forming holes in the heel seat material of said shoe and in the outsole thereof, locating an eyelet in the holes thus formed, clinching said eyelet for riveting said heel seat material and said outsole together, placing a heel on the heel seat portion of the shoe, operating a tool through said bore and said eyelet for making a hole in said heel, and inserting a fastener through said bore and into said eyelet and said hole for securing said heel to said shoe.

17. That improvement in methods of attaching a sole to a shoe mounted on a last having a bore in the heel portion thereof, which comprises operating a tool through said bore for forming holes in the heel seat material of said shoe and in the outsole thereof, locating an eyelet in the holes thus formed, clinching said eyelet for riveting said heel seat material and said outsole together, placing a heel on the heel seat portion of the shoe, operating a tool through said bore and said eyelet for making a hole in said heel, inserting a screw through said bore and into said eyelet and said hole, and operating a tool through said bore for driving said screw into said heel.

JOHN FREDERICK SMITH.
